United States Patent Office.

ELHANAN OMENSETTER, OF PHILADELPHIA, PENNSYLVANIA, ASSIGNOR
TO SAMUEL MACFERRAN, OF SAME PLACE.

Design No. 4,193, dated June 28, 1870.

DESIGN FOR IRON RAILING.

The Schedule referred to in these Letters Patent and making part of the same.

I, ELHANAN OMENSETTER, of the city of Philadelphia and State of Pennsylvania, have invented and produced a new and original Design for Iron Railing, of which the following is a specification.

The nature of my design is fully represented by the accompanying photographic illustration, to which reference is made.

The photograph represents a side elevation of a panel of a fence, composed of longitudinal rails A A' and open pales B.

The pales B are formed of links, *a*, which are ornamented by a running vine, C, which spreads each way from the lower end of the bottom link, and runs up

the links, and intertwines at the upper end of the upper link.

The rails A A' have ornamental bands, *b*, at their ends and between the pales B.

I claim as my invention—

The design for iron railing, as shown.

In testimony that the above is my invention, I have hereunto set my hand and affixed my seal, this 23d day of April, 1870.

ELHANAN OMENSETTER. [L. S.]
